INTERNAL EXPANSION ENGINE

Walter T. Kinslow, Santa Ana, Calif.

Application July 18, 1938, Serial No. 219,679

4 Claims. (Cl. 123—50)

This invention relates to internal fluid expansion engines and has particular utility when embodied with an internal combustion engine.

In internal fluid expansion engines and particularly in internal combustion engines the impulse of an expanding charge of gas under high pressure is applied to the piston when the latter is practically on dead center. The moments by which the force of the explosion are applied to rotation of the crank shaft are at this time at their minimum. The full effect of the explosion is not applied to the crank shaft therefore until much of the power developed in the explosion has been dissipated by expansion of the combustion gases.

It is an object of my invention to provide an internal fluid expansion engine in which the energy of the expanding charge is more efficiently applied to the rotation of the crank shaft thereby increasing the power of the engine and the efficiency with which fuel is utilized thereby.

The manner of accomplishing this object as well as further objects and advantages will be made manifest in the following description taken in connection with the accompanying drawings in which:

Fig. 1 is a diagrammatic cross-sectional view of an internal combustion engine comprising a preferred embodiment of my invention and illustrating the parts thereof positioned as at the moment of firing.

Fig. 2 is a longitudinal sectional view taken on the line 2—2 of Fig. 1.

Fig. 3 is a horizontal cross-sectional view taken on the line 3—3 of Fig. 1 and illustrating the intake ports and valve of the engine.

Fig. 4 is a diagrammatic operation view illustrating the parts of the engine at the moment of exhausting.

Fig. 5 is a view similar to Fig. 4 illustrating the parts of the engine at the moment of intake.

Fig. 6 is a view similar to Fig. 5 and illustrates the compression stroke of the engine.

Fig. 7 illustrates the position of the parts of the engine just prior to the moment of firing.

Referring specifically to the drawings, the engine comprising the preferred embodiment of my invention will be designated by the numeral 10. This includes a crank case 11 in which is rotatably journalled a crank shaft 12 having two cylinder crank pins 13 and a piston crank pin 14. Mounted on the crank case 11 is a water jacketed block 15 having a cylindrical bore 16 in which a hollow cylinder 17 is slidably disposed. The block 15 has an intake passage 20 which con-

ncts through a series of ports 21 with the bore 16, as shown in Figs. 1 and 3. The block has mounted thereon an intake pipe 22, the inner end of which communicates with the passage 20 and carries a flat check valve 23 which seats on the inner end of the pipe 22 and is yieldably held in closed position by a spring 24. This spring bears against an apertured guide bar 25 through which the stem of the valve 23 passes and by which it is slidably guided.

The block 15 also has a threaded recess 30 which connects through a port 31 with the sleeve bore 16, said recess being adapted to receive a spark plug 32. A suitable ignition system (not shown) is provided for firing this plug 32 in proper timed relation with the rotation of the shaft 12 as will be made clear hereinafter.

Also formed in the block 15 is a series of exhaust ports 35 which open into the block bore 16 and connect outwardly with an exhaust pipe 36 provided on the block.

The cylinder 17 is pivotally connected by connecting rods 37 to the crank pins 13 as shown in Figs. 1 and 2 so that rotation of the shaft is accompanied by the reciprocation of the cylinder 17 and the sleeve bore 16. This cylinder has a head 40 and a cylinder chamber 41. Provided in the cylinder 17 is a series of intake ports 42 which register with the intake ports 21 of the block 15 when these ports are on the same level as shown in Figs. 3 and 5. The cylinder 17 also has a firing port 43 which registers with the spark plug port 31 when these ports are on the same level as shown in Fig. 1. The cylinder 17 also has a series of exhaust ports 45 which register with the exhaust ports 35 when these ports are on the same level as shown in Fig. 4. The cylinder 17 is also provided with a pair of compression rings 46 disposed above and below the ports 42 and 43.

Slidably disposed in the cylinder chamber 41 is a piston 50 having compression rings 51 and connected by a connecting rod 52 to crank pin 14 so that reciprocation of the piston 50 in the cylinder chamber 41 imparts rotation to the shaft 12.

Operation

The engine 10 of my invention is preferably of the two cycle type in which a charge of fuel is fired during each revolution of the shaft 12. Fig. 1 shows the engine at the point of firing in which a charge of fuel compressed between the piston 50 and the cylinder head 40 is fired by the spark plug 32 through the ports 31 and 43 which are here in registry. It is to be noted that this firing takes place with the piston crank pin 14 dis-

posed at an angle of approximately 45 degrees past dead center. The power of explosion when this is at its maximum is thus applied to the crank pin 14 when the latter is so disposed that 5 the torque moments with which this power is applied to the crank shaft 12 are substantially at their maximum. In other words, the expansive force of the explosion in the cylinder 17 is given the greatest leverage on the shaft 12 when 10 this expansive force is at its peak.

The operation of the engine 10 so as to effect this result is as follows:

Figs. 4, 5, 6 and 7 show successive situations in a single revolution of the shaft 12 beginning 15 with the firing position as shown in Fig. 1 and ending up just prior to reaching the next firing position.

Fig. 4 shows the piston 50 after it has moved 20 downwardly to uncover the exhaust port 45 just as the latter comes into registry with the exhaust ports 35, the force of the explosion in the cylinder here being spent so that it is desirable to get rid of the gases of combustion at this point. This 25 exhaust is of the usual two cycle type and is therefore not entirely completed before the upward movement of the cylinder 17 moves the ports 45 and 35 out of registry as shown in Fig. 5 and brings the intake ports 42 and 21 into registry. The latter takes place at a time when 30 further downward movement of the piston, in conjunction with the cooling of the remaining gases of combustion, has produced a semi-vacuum in the cylinder chamber 41 above the piston. This results in a gaseous fuel mixture furnished 35 through the intake pipe 22 being sucked inwardly past the valve 23 and through the passage 20 and ports 21 and 42 into the cylinder chamber 41.

The rising of the cylinder 17 cuts off the intake ports 21 and 42 and the compression stroke 40 which is shown in progress in Fig. 6 now takes place.

As the piston 50 nears its uppermost position, the cylinder 17 starts downwardly until the maximum compression stroke is arrived at approximately 45 at the point illustrated in Fig. 7. Here it is seen that the ports 42 and 21 have again come into registry with the result that a small amount of compressed fuel is expelled through these ports into the passage 20 which in engine 50 design practice is made so small that the amount of compression lost by this is negligible. The valve 23 of course prevents passage of this fuel into the pipe 22. From the point shown in Fig. 7, the cylinder 17 and piston 50 both move downwardly only a short distance before the ports 55 42 are shifted out of registry with the ports 21 and the port 43 is brought into registry with the spark plug port 31 at which time the spark plug fires the charge of fuel compressed in the upper

end of the cylinder chamber 41 thus initiating another cycle of operation similar to the one just described.

What I claim is:

1. In an internal combustion engine, the combination of: a cylinder having intake and exhaust ports communicating therewith; a piston in said cylinder; a reciprocal head forming a combustion chamber in said cylinder between said head and said piston; a crank shaft having primary and secondary cranks thereon; means connecting said primary crank with said piston and said secondary crank with said reciprocal head, said cranks being so related as to cause said piston and said reciprocal head to move relatively apart 15 during the power stroke of said piston; means for opening and immediately closing said exhaust port when said combustion chamber has expanded to substantially three-fourths of its greatest volume; and means for opening said intake port 20 when said combustion chamber has expanded to substantially its greatest volume.

2. A combination as in claim 1, in which the throw of said secondary crank is substantially one-half that of said primary crank and in which 25 said secondary crank is positioned substantially ninety degrees ahead of said primary crank.

3. In an internal combustion engine, the combination of: a block having a bore formed therein, said block including intake and exhaust ports 30 communicating with said bore; a cylinder reciprocal in said bore and having intake and exhaust ports formed in the wall thereof for registration with the intake and exhaust ports of said block; a head provided on said cylinder; a piston 35 reciprocal in said cylinder, said piston and said head forming a combustion chamber in said cylinder; a crank shaft having primary and secondary cranks thereon; and means connecting said primary crank with said piston and said secondary crank with said reciprocal cylinder, said cranks being so related as to cause said piston and said reciprocal head to move relatively apart during the power stroke of said piston, the exhaust port of said cylinder moving into and 45 out of registration with the exhaust port of said block when said combustion chamber has expanded to substantially three-fourths of its greatest volume, said intake port of said cylinder moving into and out of registration with the in- 50 take port of said block when said combustion chamber has expanded to substantially its greatest volume.

4. A combination as in claim 3, in which the throw of said secondary crank is substantially 55 one-half that of said primary crank and in which said secondary crank is positioned substantially ninety degrees ahead of said primary crank.

WALTER T. KINSLOW.
